CLAIM

The ornamental design for a smoke detector flush mount, as shown and described.

DESCRIPTION

FIG. 1 is a perspective view of a smoke detector flush mount, showing my new design;

FIG. 2 is a side view thereof;

FIG. 3 is a side long view thereof;

FIG. 4 is a top view thereof;

FIG. 5 is a bottom view thereof;

FIG. 6 is a perspective view of a smoke detector flush mount, showing my new design;

FIG. 7 is a side view thereof;

FIG. 8 is a top view thereof; and,

FIG. 9 is a bottom view thereof.

The broken lines depict unclaimed environmental subject matter.
